ATTORNEY

UNITED STATES PATENT OFFICE.

ANTHONY W. KRIEG, OF NEW YORK, N. Y.

CAKE ORNAMENT.

Application filed June 3, 1927. Serial No. 196,251.

My invention relates particularly to candle holders intended for ornamenting birthday cakes and the like.

The main object is to provide an attractive inexpensive candle holder which is practically indestructible and will hold candle drip.

Another object is to provide a type of construction which is adapted to be embodied in various ornamental designs, such as, roses, orange blossoms, lilies, etc.

In carrying out the invention I form the main body of the holder of sheet metal designed to simulate a flower. The interior 15 is provided with a candle socket, the parts being so proportioned and arranged as to accommodate the dripping of the candle and also so as to prevent the candle wick from setting fire to the cake.

20 The ornament is provided with an elongated pin or stem adapted to be inserted in the cake.

Fig. 1 is a vertical sectional view showing one type of construction embodying my 25 invention.

Fig. 2 is a vertical sectional view showing another modification.

The body 5 or casing is formed of sheet metal to simulate such ornamental flower 30 or other design as is desired. The candle holding socket 6 is preferably somewhat larger at the top than it is at the bottom and resilient. In the form shown in Fig. 1 this socket consists of an open helix of 35 spring wire having a stem 7 extending through the bottom of the casing. The bottom 8 of the casing is somewhat contracted to provide a recess which may be undercut to receive the lower turn of the helix so as to resiliently hold the helix in place without requiring solder or other mechanical operations. The helix may be sprung into place and held by its own expansive tendency.

40 The lower part of the casing may also be provided with a flange-like portion 9 simulating the sepals of a flower. The upper part or mouth 10 of the casing is

preferably sufficiently larger than the candle 11 to permit candle drip to run down 50 into the casing which thus prevents the candle from dripping or falling over on to the cake (not shown).

In the form shown in Fig. 2 the casing 12 is flared outwardly to resemble a different design. The sepals 13 may be formed in one piece separate from the petal portion 12 of the casing. The candle holder 14 may also be formed of sheet metal and is 55 preferably split so as to provide a resilient 60 cup-like receptacle for the lower end of the candle. This form of construction also permits a somewhat larger candle to be inserted and gripped in the tapered portion 65 15 if desired. The stem 16 may be formed 165 of a separate wire and provided with a head 17, the stem passing through the bottom of the holder 14, the casing 12 and the sepals 13.

Other modifications may be made within 70 the spirit of my invention as set forth in the following claims.

I claim:

1. An ornamental candle holder comprising a sheet metal casing simulating a 75 flower design, a resilient candle holder secured therein and a supporting wire extending through the bottom of the casing, said casing having a candle-drip receiving recess surrounding said socket.

2. A candle holder comprising an ornamental casing of metal simulating the design of the petals of a flower, metallic sepals around the base of the casing, a candle socket within the casing, a wire extending from the bottom of the sepals, said casing having a candle-drip receiving recess surrounding said socket.

3. A candle holder comprising a metallic casing having a restricted recess in the bottom, a candle socket resiliently expanded in said recess and a wire for mounting said holder in a cake, said casing having a candle-drip receptacle around said socket.

ANTHONY W. KRIEG.
